CLAIM

The ornamental design for a fire hydrant flow meter with handles, as shown and described.

DESCRIPTION

FIG. 1 is a perspective view of a fire hydrant flow meter with handles showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof; and,

FIG. 7 is a rear elevational view thereof.

The broken lines shown in the figures are included for the purpose of illustrating environment which form no part of the claimed design.
